UNITED STATES PATENT OFFICE.

MAXIMILIAN WAPPICH, OF SACRAMENTO, CALIFORNIA.

IMPROVEMENT IN PRESSES.

Specification forming part of Letters Patent No. 29,928, dated September 4, 1860.

To all whom it may concern:

Be it known that I, MAXIMILIAN WAPPICH, of Sacramento, in the State of California, have invented and made certain new and useful Improvements in Presses for Cotton, Hay, or other Articles; and I do hereby declare that the following is a full, clear, and exact description of the construction and operation of the same, reference being had to the annexed drawings, making part of this specification, wherein—

Figure 1 is a side view of said press. Fig. 2 is a vertical section at the line *x x*, and Fig. 3 is an end elevation.

Similar letters of reference denote the same parts.

The nature of my said invention consists of pawls acted on by a cross-shaft, and revolving inclines that give motion to the platen that compresses the goods, and the operation of the parts is resisted by yielding journal-boxes, so that the parts are more reliable, as they are not subjected to a sudden and unyielding strain.

I have represented my press as standing vertically, but the same may be placed horizontally or inverted, if desired; and the press is shown as single, but it may be made double, if desired.

In the drawings, *a* is the lower platen, on which are the standards or side frames, *b b*, of any desired character. Between these frames is a wheel, *c*, whose circumference is not circular but fluted, forming a series of inclined planes. This wheel *c* is on a shaft, *d*, that is set in journals 1 1 in the side frames, *b*, and above each of these journals is a rubber or other suitable spring, 2, for a purpose herein-after mentioned.

3 3 are boxes or journals carrying the cross-bar or roller *e*, and 4 4 are springs to keep the roller *e* and parts attached up to the fluted wheel *c*.

5 5 are journals or blocks around the axis of the roller *e* near the boxes 3 3, said blocks being within the ratchet-frames *f f*, that connect at their lower ends to the follower or platen *g*. These frames *f f* may be guided in slides or by rollers on the side frames, *b*.

6 6 are pairs of pawls attached to the blocks 5 5, and kept to the teeth of the ratchet-frames *f f* by springs, and 7 7 are pairs of pawls (see dotted lines, Fig. 2) on a block around the shaft *d*, near each end thereof.

The operation is as follows: The bale or bundle to be pressed is laid between the plat-

en *a* and follower *g*, and the shaft *d* and fluted wheel *c* revolved by competent power. The roller *e* is forced down by the inclined surface between each flute, carrying with it the pawls 6 6, frames *f f*, and follower *g*, and the pawls 7 7 retain the frames *f f* at the point to which they are forced down by each movement of the roller *e* until the necessary pressure is obtained upon the bale or bundle. In all cases the springs 2 2, intervening between the journal-box of the shaft *d* and the side frames, *b b*, yield under the pressure and prevent any sudden strain on the parts as the inclined or fluted surface of *c* comes in contact with the roller *e*. After the bale is pressed, the pawls are to be released by the cords or chains 8 8, so that the frame *f* will slide back out of the way; or, if desired, the platen *g* may be detained by a latch-lever while the pawls are being disconnected from the ratchet-frame *f*; and when the press is vertical the follower *g* has to be drawn up out of the way for the next bale. To accomplish this, I provide the drums *h h*, that are coupled to or disconnected from the wheel *c* by sliding them endwise on the shaft *d*. When in contact with pins 9 9 in *c*, the drums *h h* are coupled thereto and rotate therewith, so as to hoist the platform or follower *g* by the chains or ropes 10 10 to said drums *h h*, the pawls 6 and 7 of course being kept from contact with the ratchet-frames *f* by the cords 8, or other suitable device. The drums *h h* and chains or ropes 10 10 will also act to draw the platen along when horizontal; or other devices may be used for moving this follower or platen *g*.

It will be evident that the ratchet-frames *f* might be connected to intervening levers between their ends and the follower *g*, so as to make the power progressive.

My press may be applied for cotton, hay, tobacco, hops, oil, cider, or for any other articles to which it may be applicable.

What I claim as my invention, and desire to secure by Letters Patent, is—

The ratchet-frames *f f* and pawls 6 6, acted on by the roller *e* and fluted wheel *c*, as and for the purposes specified.

In witness whereof I have hereunto set my signature this 2d day of August, 1860.

MAXIMILIAN WAPPICH.
